UNITED STATES PATENT OFFICE.

ANTHONY JOHN STAFF, OF COLORADO SPRINGS, COLORADO.

ELECTRIC INCUBATOR.

Application filed March 28, 1924. Serial No. 702,701.

To all whom it may concern:

Be it known that I, ANTHONY J. STAFF, a citizen of Austria-Hungary, residing at Colorado Springs, in the county of El Paso and State of Colorado, have invented new and useful Improvements in Electric Incubators, of which the following is a specification.

This invention relates to incubators, and 10 has for one of its chief characteristics, the provision of a structure wherein chicks are hatched with a greater degree of certainty, especially in dry climates, wherein incubators are not particularly successful, and a 15 structure wherein the chicks hatched are as good as hen hatched chicks in health, vigor and development.

An essential characteristic of the invention resides in the provision of means for 20 uniformly distributing the heat over the eggs, and transmitting the heat to the upper surface thereof, the location of the germ during incubation, rather than heating air which circulates about and contacts all 25 points of the surface of the eggs. By reason of this structure, the eggs are not dried out abnormally, as in the case where warm air contacts with the whole area of the eggs, thereby making the element of moisture un- 30 necessary, even in dry climates.

The nature and advantages of the invention will be better understood when the following detailed description is read in connection with the accompanying drawings, 35 the invention residing in the construction, combination and arrangement of parts as claimed.

In the drawings forming part of this application, like numerals of reference indicate similar parts in the several views, and wherein:

Figure 1 is a perspective view partly broken away.

Figure 2 is an enlarged sectional view 45 taken on line 2—2 of Figure 1.

Figure 3 is a sectional view taken on the line 3—3 of Figure 2.

Figure 4 is a detail view of the heating element.

Figure 5 is a detail view of the egg tray.

Figure 6 is a diagrammatic view.

The incubator forming the subject matter of the present invention consists of a box like body portion 10 which may or may 55 not be supported by suitable legs 11. The incubator is provided with a hinged cover

12 of substantially the same configuration as the body portion 10, the cover being normally latched to the body portion by any suitable means, such as indicated at 13. 60 The bottom of the body portion includes oppositely inclined quarters or sections 14 with the center lying in a plane beneath the opposed side edges as clearly shown in Figure 2. Each section of the bottom is adapted to support one or more of the egg trays shown in Figure 5 and indicated at 15. Each tray is provided with a series of spaced parallel partitions 16, and arranged transversely of these partitions is a series of 70 spaced parallel coiled springs 17. The eggs indicated at 16' are adapted to be arranged in rows between each pair of springs 17 in the manner clearly shown in Figure 3. Arranged within the cover 12 is a heating element in the nature of a rectangular frame of wire or the like covered by asbestos and upon which is wound a resistance wire 18. This heating element is supported in any suitable manner within the cover 12, and directly above what I term a heat distributing element 19. This latter mentioned element preferably consists of a tanned animal skin arranged with the fur side 20 to contact the eggs when the cover is closed, so that the heat transmitted from the heating element 18 will be conveyed to the element 19, and uniformly distributed over the eggs supported by the tray 15. The fur portion or side of the heating element only contacts the 80 adjacent surfaces of the eggs, so that the heat enters the eggs from the top, or rather the point of location of the germ during incubation. It will be further noted that the heat distributing element 19 is given the 85 same shape or configuration as that of the bottom 14, the highest point being at the corners of this element and the lowest point in the center, and it is by reason of this peculiar shape that the heat is more evenly distributed over the eggs. As above stated, the eggs rest between each pair of springs 90 17 forming part of the egg tray which holds the eggs against the fur side of the heat distributing element 19, with a slight pressure 100 thereby assuring contact therewith, irrespective of the variation in the size of the eggs. Then again, these springs form a sort of trackway to permit the eggs to be turned with a minimum of time and effort, as it is 105 only necessary to remove one egg from each end of the row, to allow the remainder of 110

the eggs of said row to be rolled and turned, after which the eggs which have been removed are again placed on the track at the ends of the row. The heat distributing element 19 may be supported in any suitable manner within the cover 12 but is preferably secured to a cross piece 21 as clearly shown in the drawings. By reason of this construction and arrangement of parts, it is obvious that I have provided a natural mode of incubation, in that it closely imitates the hen, by transmitting the heat to the upper surfaces of the eggs rather than heating air which merely circulates around the eggs and contacts all points of their surfaces. It is by reason of the same fact as that just mentioned that the eggs do not dry out abnormally which they do where warm air circulating about the eggs and contacting the entire area thereof is used, for incubation, and furthermore my method and structure eliminate the addition of moisture, which is usually required in other incubators and more especially in dry climates.

25 The heating element 18 above referred to is of course included in circuit shown in diagrammatic view wherein 22 represents a condenser. This circuit also embodies a thermostatically controlled circuit breaker 30 wherein the fixed contact is indicated at 23, and the movable contact at 24. This latter mentioned contact is carried by an arm 25 arranged in the path of movement of a shaft 26 having an insulated covering 27 on its free end. This shaft 26 is connected to the movable side of the thermostat 28, the opposite side of which is supported by a shaft 29 which is threaded for a portion of its length as at 30, and which threaded portion is 40 threaded through an opening in a plate 31 arranged within the cover 12. It is obvious that as the heat reaches a predetermined temperature within the incubator, causing an expansion of the thermostat 28, that the shaft 26 is moved against the arm 25 to separate the contact 24 from the contact 23 thereby breaking the circuit. The degree of temperature necessary to break this circuit can be easily regulated by adjusting the 45 thermostat 28 through the instrumentality of the shaft 29, the other end of which is equipped with a knob 32 for this purpose. Supported on the side of the cover is a graduated dial 33 and carried by the knob 32 is 50 an indicating finger 34 so that a more accurate adjustment can be made. Also included in circuit and connected in series

with the heating element are electric light bulbs 34, the wires for which are indicated at 26. 60

While it is believed that from the foregoing description, the nature and advantages of the invention will be readily apparent, I desire to have it understood that I do not limit myself to what is herein shown and described, and that such changes may be resorted to when desired as fall within the scope of what is claimed. 65

Having thus described the invention, I claim: 70

1. An incubator comprising a box like body portion and including a bottom having oppositely inclined sections, egg trays adapted to be supported on said bottom and including spaced parallel resilient elements 75 between which the eggs are supported, an electric circuit, an electric heating element included in said circuit, automatically operable means for regulating the temperature of the incubator, a flexible heat distributing element having a fur side arranged to contact the adjacent surface of said eggs, whereby the heat is uniformly distributed from said heating element to the eggs, said resilient elements of the egg tray supporting the eggs with a slight pressure against said heat distributing element, said element having a configuration similar to that of said bottom. 80

2. An incubator comprising a box like body portion, and a hinged cover, said body portion including a bottom having oppositely inclined sections with the corners constituting the highest points, egg trays adapted to be supported by said bottom, an electric circuit, a heating element included in said circuit and supported within the cover, a flexible heat distributing element supported by the cover directly beneath said heating element and having a configuration 95 similar to that of the bottom, said heating element consisting of an animal skin having its fur arranged to contact the adjacent surfaces of the eggs and thereby convey the heat from the heating element to the said eggs uniformly, an electric light bulb connected in parallel with said heating element, a circuit breaker, and thermostatically operated means for controlling said circuit breaker, said means being adjustable whereby the incubator can be maintained at any desired temperature. 100

In testimony whereof I affix my signature.
ANTHONY JOHN STAFF.
